UNITED STATES PATENT OFFICE

104,496

DESIGN FOR AN ELASTIC FABRIC

Otto Eugene Huber, Reading, Pa., assignor to
The Narrow Fabric Company, West Reading,
Pa., a corporation of Pennsylvania

Application November 21, 1936, Serial No. 66,063

Term of patent 7 years

To all whom it may concern:

Be it known that I, Otto Eugene Huber, a citizen of the United States of America, residing at Reading, in the county of Berks and State of Pennsylvania, have invented a new, original, and ornamental Design for an Elastic Fabric, of which the following is a specification, reference being had to the accompanying drawing, forming part thereof.

Figure 1 discloses a portion of elastic fabric embodying my ornamental design, to which no tension is applied.

Fig. 2 discloses a portion of the elastic fabric depicted in Fig. 1, as it appears when subjected to tension substantially equivalent to that incident to normal use.

Fig. 3 is a cross-sectional view of the fabric

shown in Fig. 1, taken as indicated by the arrows 3—3 on said figure.

Fig. 4 is a cross-sectional view of the fabric shown in Fig. 2, taken as indicated by the arrows 4—4 on said figure.

Fig. 5 is a cross-sectional view of the fabric shown in Fig. 1, taken as indicated by the arrows 5—5 on said figure.

The figures disclose the elastic fabric enlarged to approximately one and one-half times normal size, so that they will be approximately full size upon the reduction of the same to the ultimate size as appearing in the patent copy.

I claim:

The ornamental design for an elastic fabric as shown and described.

OTTO EUGENE HUBER.
